MOTOR SCOOTER

Jim May, 12110 SE. Pine, Portland, Oreg.

Filed Apr. 19, 1962, Ser. No. 69,771

Term of patent 14 years

(Cl. D90—8)

FIGURE 1 is a side elevational view of a motor scooter, showing my new design;

FIGURE 2 is an elevational view taken from the other side of the motor scooter;

FIGURE 3 is a rear elevational view; and

FIGURE 4 is a top plan view.

I claim:

The ornamental design for a motor scooter, as shown.
